UNITED STATES PATENT OFFICE.

JOHN A. LAFLER, OF ALBION, NEW YORK.

BRICK-MACHINE.

SPECIFICATION forming part of Letters Patent No. 289,422, dated December 4, 1863.

Application filed May 14, 1863. (No model.)

To all whom it may concern:

Be it known that I, JOHN A. LAFLER, a citizen of the United States, residing at Albion, in the county of Orleans and State of New York, 5 have invented certain new and useful Improvements in Brick-Machines; and I do hereby declare the following to be a full, clear, and exact description of the invention, such as will enable others skilled in the art to which it appertains 10 to make and use the same.

This invention relates to brick-machines; and it consists in providing certain new and useful improvements in the construction of that type of brick-machines which are shown in 15 patents granted to me January 6, 1863, No. 37,348, and August 11, 1868, No. 80,976, which improvements will fully appear in the following general description and claims.

The present invention is fully illustrated in 20 the accompanying drawings, as follows:

Figure 1 is a vertical longitudinal section on the line *xx* in Fig. 2. Fig. 2 is a plan view of the press-bed *E*, with parts above removed. Fig. 3 is a transverse vertical section of the 25 press-box, or that part of the press-box which is fixed. Fig. 4 is a perspective view of the sliding cover of the press-box. Fig. 5 is a perspective view of the fixed part of the press-box.

A is the grinding-mill. 30 *B B'* is the telescopic press-box, of which the part *B* is fixed to the frame of the grinding-mill, and the part *B'* to the vertically-moving press-bed.

C is the space which is occupied by the mold 35 when being filled, and *c c c* are rollers below the mold.

D is the sliding cover of the press-box, and *D' D''*, &c., is the gearing for operating the said cover. 40

E is the press-bed, and *E' E''* is the gearing for operating the said press.

F is a packing-strip for preventing the escape of clay with the sliding cover *D*, and *F'* is a spring for keeping the strip *F* close against 45 the under side of the cover.

G is a cam which supports the outer end of the inner frame, *E''*, of the press-frame, and by which it can be dropped at that end to avoid damage from stones while pressing, if found 50 necessary.

The general operation of the machine is as

follows: The clay, when properly ground, finds its way into the presser-box *B B'*. From thence it is forced into the molds located at *C* whenever the press-bed is raised, and the press-box 55 is collapsed or telescoped together. The cover *D* is always slid into place over the top of the press-box before the parts are telescoped, so that it will offer a resistance to the upward movement of the clay as the parts are telescoped. When the pressing is taking place, if it should be found there was anything in the clay—like large stones, for instance—that would damage the press or molds, the cam *G* can be tripped by moving the lever *G'*, and 60 the inner frame, *E''*, which holds the molds, will drop down and relieve the press.

The parts of the construction here shown which are thought to be new are as follows: The gearing by which the cover *D* is operated, 70 the construction and adjustment of the packing-strip *F*, the gearing for pushing the molds along on the table or press-bed, and the application of the cam *G*.

The cover *D* moves on slides *d d'* on each side of the frame. It is connected with a rocking lever, *D'*, by the rod *D''*, which attaches to it at *D'*. The rocking lever is operated from the lever *D''*, and this from a pitman, *D''*, from the gearing-wheel *D'*. The pitman *D''* has 75 a slot, *d''*, where it connects with the lever *D'*, which gives a dwell in the action of the gearing connected with the cover, so that the cover moves over the box *B* and dwells, then moves off and dwells during each revolution of the 80 wheel *D'*. It is during the dwell of the cover over the box that the press must act.

In my patent of 1868 above referred to, where I first show the cover, it was moved by gearing on the lower end of the mill-shaft, and had no 90 provision for dwells, except such as a crank gives. The manner of gearing here shown is much superior as to strength and time of action.

I have found it necessary that the cover *D* shall move through a packed orifice in the side 95 of the box, or else it will soon clog with clay. To this end I apply the strip *F*, as shown, under the cover. This strip has a wide face, giving a good wide bearing, which of itself prevents clay working through, and then the strip 100 is kept firmly in contact with the cover by rubber springs *F'*, which are tempered by screws *F''*.

The molds are laid upon the table or press-bed E², above the space C, and are pushed under the box B' by a pusher, C', which is connected by links C² with cranks C³ on a rock-shaft, C⁴, which is rocked by a sector-lever, C⁵, chain and rod C⁶, and the hand-lever C⁷.

When the press is operated from a hand-windlass, E⁵, there is no necessity of the cam G and lever G', for the operator can always tell 10 by feeling whether there are any obstructions in the clay; but when this windlass is operated from some of the moving parts of the machinery, it is necessary to have some way of relieving the press. Then, again, when it is operated by 15 machinery, it is often desirable to gain time in which to shift the molds. This can all be accomplished by having the inner part of the bed E² pivoted independently on the frame E, as at E³, and supporting the outer end by a 20 detachable device. As soon as the pressure has been applied, the operator can trip the cam G, and the bed E² will drop down in advance of the frame E, and by the time the said frame E is ready to move up again the molds 25 may have been shifted and the cam reset.

What I claim as new is—

1. In a brick-machine substantially as shown,

the combination, with the press-box B B', of the sliding cover D, operated by the gearing D³ D⁴ D⁵, slotted pitman D⁶, and wheel D⁷, arranged 30 to operate substantially as and for the purposes set forth.

2. In a brick-machine, the combination, substantially as shown, of the press-box B, the packing-strip F, spring F', and sliding cover D. 35

3. In a brick-machine substantially as shown, the combination, with the press-bed E E² and press-box B', of the mold-push C', links C² C², cranks C³ C³, rock-shaft C⁴, sector C⁵, chain and rod C⁶, and hand-lever C⁷, arranged to operate 40 substantially as and for the purposes set forth.

4. The combination, in a brick-machine substantially as shown, of the press-frame E, pivoted at E', the contained frame E², pivoted on said frame E, as at E³, and the trip-cam G G', 45 for holding the said frame E² even with the frame E, or allowing it to drop independently, as and for the purposes set forth.

In testimony whereof I affix my signature in presence of two witnesses.

JOHN A. LAFLER.
